UNITED STATES PATENT OFFICE.

TONY BUH, OF REITZ, PENNSYLVANIA.

COMBINED LADDER AND CHAIR.

1,359,486.

Specification of Letters Patent. Patented Nov. 23, 1920.

Application filed March 9, 1920. Serial No. 364,369.

To all whom it may concern:

Be it known that I, TONY BUH, a citizen of the United States of America, residing at Reitz, in the county of Somerset and State of Pennsylvania, have invented certain new and useful Improvements in Combined Ladders and Chairs, of which the following is a specification.

This invention relates to a certain new and useful combined ladder and chair particularly adapted for use in and around dwellings, the device presenting a ladder construction which may be readily converted from one type adapted to be braced against a wall to another type wherein the ladder *per se* is propped without requiring wall support.

The principal object of the invention is to provide a ladder of the above kind which, when tilted in one direction, will be propped for use in open space with the steps thereof horizontally disposed, and which when tilted in the opposite direction is adapted to be leaned against a wall or other support and still have its steps horizontally disposed.

With the above general objects in view and others that will become apparent as the nature of the invention is better understood, the same consists in the novel form, combination and arrangement of parts herein-after more fully described, shown in the accompanying drawings and claimed.

In the drawings wherein like reference characters indicate corresponding parts throughout the several views,

Fig. 1 is a side elevational view of a combined ladder and chair constructed in accordance with the present invention, the same being partly broken away,

Fig. 2 is a front elevational view thereof,

Fig. 3 is a view similar to Fig. 1 with the ladder in oppositely tilted position,

Fig. 4 is an enlarged horizontal sectional view taken substantially upon line IV—IV of Fig. 1,

Fig. 5 is an enlarged sectional view taken substantially upon line V—V of Fig. 3,

Fig. 6 is an enlarged sectional view taken upon line VI—VI of Fig. 3,

Fig. 7 is an enlarged sectional view taken substantially upon line VII—VII of Fig. 3, and

Fig. 8 is an enlarged fragmentary sectional view taken substantially upon line VIII—VIII of Fig. 1.

Referring more in detail to the several views, the present invention embodies a partial chair construction of common form embodying a seat or chair bottom 5 having supporting legs 6 at each corner which are braced and connected by rungs 7.

The seat 5 is provided with longitudinal elongated slots at each side thereof as at 8 adjacent the rear edge of the same, and the lower ends of the side rails 9 of the ladder *per se* are pivotally mounted in these slots by means of pins 10 or the like which are carried by the seat 5. The ladder is provided with a pair of props 11, each of which are pivotally and slidably attached by means of a pin and slot connection 12 to the upper ends of the side rails 9, the lower ends of the props 11 being slidably disposed within longitudinal side grooves 13 provided in the upper face of the seat 5. The lower ends of the props 11 have transverse pins 14 secured therein, and a plate 15 is secured on the upper surface of the seat 5 so as to partially cover the grooves 13 and engage the pins 14 so as to retain the lower ends of the props 11 within the grooves 13. The plates 15 are provided with longitudinal slots 16 of such length as to permit the lower ends of the props 11 to slide backwardly and forwardly relative to the seat 5, and the side rails 9 are connected to the props 11 by the usual links 17 adapted to hold the ladder in propped condition in the usual and well known manner. The side rails 9 are preferably rigidly connected by transverse braces 18 or the like which hold said side rails in proper spaced relation.

A plurality of flat steps 19 are pivoted adjacent their forward edges between and to the side rails 9 as at 20, and these steps project rearwardly and are pivotally attached as at 21 to a pair of side strips 22, one strip 22 being arranged parallel with and adjacent to each side rail 9, and the strip 22 being substantially of the same length as the side rails 9 as seen in Figs. 1 to 3 inclusive. The plate 15 is provided at its rear end with an upstanding bracket 23 composed of a pair of ears to which the lower ends of the links 24 are pivotally connected by means of pins 25, there being a pair of links 24 for each strip 22, and each pair of links 24 being pivotally mounted at the sides of a strip 22 adjacent the lower end of the ladder as at 26. A step 27 is pivotally mounted as at 28 to and between

2
 the rear pair of legs 6, and a bail 29 has its central portion pivotally extended through a transverse opening in the step 27, while its free ends are bent downwardly and headed so as to slide within the longitudinal grooves 30 provided in said legs 6, the heads upon the ends of the bail 29 being engaged by slotted cover plates 31 so that the same are retained in the grooves 30 and allowed sliding movement therein. It will thus be apparent that the step 27 may be propped by the bail 29 in an operative horizontal position as seen in Fig. 1 or will be permitted to swing upwardly to a substantially vertical 10 inoperative position as seen in Fig. 3.

15 With the parts of the device disposed as shown in Fig. 1, if it is desired to move the various parts so as to provide a wall supported ladder, it is merely necessary that 20 the rails 9 be swung rearwardly to the position of Fig. 3. When this is done upward movement is imparted to the strips 22 through the links 24 so as to maintain the steps 19 always horizontally disposed or 25 substantially so. It is of course to be understood that the joint between the links 17 is first broken before the rails 9 are pushed rearwardly so that the props 11 can move in the grooves 13 rearwardly, and the 30 props 11 can move downwardly with respect to the upper ends of the rails 9 through the provision of the pin and slot connection 12. When the parts are thus brought to the position of Fig. 3, the ladder may be leaned or 35 against a wall and conveniently used, or the ladder may act as a chair back when the seat 5 is used as a chair member. A reverse of this operation takes place when the parts are shifted forwardly from the 40 position of Fig. 3 to the position of Fig. 1. It will also be obvious that a propped ladder construction is provided when the parts are disposed as shown in Fig. 1 so that it is not necessary to lean the ladder against a 45 wall when making use of the same. When the device is used as a propped ladder, the step 27 becomes serviceable in mounting the ladder, while the seat 5 may be employed for this purpose when the device is used in 50 its condition of Fig. 3.

From the foregoing description it is believed that the construction and operation of the present invention as well as the advantages thereof will be readily understood 55 and appreciated by those skilled in the art.

Minor changes may be made without departing from the spirit and scope of the invention as claimed.

What I claim is:

60 1. In a ladder of the class described a support, a pair of upwardly extending side rails rigidly connected in spaced substan-

tially parallel relation and having their lower ends pivoted on said support, a pair of props slidably connected at their lower ends with the support for limited movement toward and away from the lower ends of said side rails and pivotally and slidably connected at their upper ends to said side rails, a plurality of flat steps pivotally mounted between said side rails, and means connected to said support and to said steps for operatively maintaining the steps horizontally disposed at all times when the ladder is swung upon the pivots at the lower 75 ends of said side rails.

2. In a ladder of the class described a support, a pair of upwardly extending side rails rigidly connected in spaced substantially parallel relation and having their lower ends pivoted on said support, a pair of props slidably connected at their lower ends with the support for limited movement toward and away from the lower ends of said side rails and pivotally and slidably connected at their upper ends to said side rails, a plurality of flat steps pivotally mounted between said side rails, means connected to said support and to said steps for operatively maintaining the steps horizontally disposed at all times when the ladder is swung upon the pivots at the lower 80 ends of said side rails, said last named means comprising a pair of strips extending upwardly from the support in spaced substantially parallel relation with the side rails and pivoted to said strips, and links pivotally connected to said support and to the lower ends of said strips.

3. In a device of the class described, a flat base having longitudinal side grooves, a pair of upwardly extending side rails pivoted at their lower ends adjacent the rear ends of said grooves upon horizontal pivots, a pair of props slidably and pivotally connected at their upper ends to the upper ends of said side rails, transverse pins carried upon the lower ends of said props within said grooves, slotted cover plates for said grooves engaging said pins for retaining the lower ends of said props in said grooves while permitting movement of the lower ends of said props toward and away from the lower ends of said side rails, steps pivotally mounted between said side rails, and means operatively connecting said steps with said base for maintaining the steps horizontally disposed at all times when the props and side rails are moved relative to the base for converting the device from a wall supported 11 ladder to a propped one.

In testimony whereof I affix my signature.

TONY BUH.
